(57) **CLAIM**

I claim the ornamental design for a multi-degree-of-freedom surgical clip, as shown and described.

DESCRIPTION

FIG. 1 is a top perspective view of a multi-degree-of-freedom surgical clip comprising a new, original and ornamental design, in a first example use configuration; FIG. 2 is a bottom perspective view of the multi-degree-of-freedom surgical clip shown in FIG. 1;

FIG. 3 is a front view of the multi-degree-of-freedom surgical clip shown in FIG. 1; FIG. 4 is a rear view of the multi-degree-of-freedom surgical clip shown in FIG. 1;

FIG. 5 is a left side view of the multi-degree-of-freedom surgical clip shown in FIG. 1;

FIG. 6 is a right side view of the multi-degree-of-freedom surgical clip shown in FIG. 1;

FIG. 7 is a top view of the multi-degree-of-freedom surgical clip shown in FIG. 1;

FIG. 8 is a bottom view of the multi-degree-of-freedom surgical clip shown in FIG. 1;

FIG. 9 is a front perspective view of the multi-degree-of-freedom surgical clip shown in FIG. 1, in a second example use configuration;

FIG. 10 is a front view of the multi-degree-of-freedom surgical clip shown in FIG. 9;

FIG. 11 is a rear perspective view of the multi-degree-of-freedom surgical clip shown in FIG. 1, in a third example use configuration; and,

FIG. 12 is a right side view of the multi-degree-of-freedom surgical clip shown in FIG. 11.

The broken lines shown in the drawings are included for the purpose of illustrating portions of the multi-degree-of-freedom surgical clip, and form no part of the claimed design.
